UNITED STATES PATENT OFFICE.

CHARLES W. BECK, OF DETROIT, MICHIGAN.

PRIMING-CUP.

1,380,345.

Specification of Letters Patent.

Patented June 7, 1921.

Application filed December 29, 1917. Serial No. 209,395.

To all whom it may concern:

Be it known that I, CHARLES W. BECK, a citizen of the United States of America, residing at Detroit, in the county of Wayne and State of Michigan, have invented certain new and useful Improvements in Priming-Cups, of which the following is a specification, reference being had therein to the accompanying drawings.

10 This invention relates to priming cups and refers more particularly to priming cups as are used in connection with automobile, marine and other internal combustion engines.

15 The invention resides in the provision of a priming cup which can be economically manufactured; in a construction in which the valve will readily center itself upon the valve seat; and further in certain novel features of construction and arrangements of parts as will more fully hereinafter appear.

In the drawings:

Figure 1 is a side elevational view, partly in section, showing a priming cup embodying my invention;

Fig. 2 is a cross-section on the line 2—2 of Fig. 1;

Fig. 3 is a top plan view, partly in section, on the line 3—3 of Fig. 1;

30 Fig. 4 is an enlarged perspective view of the insert;

Fig. 5 is a vertical sectional view through a modified construction of valve.

Describing in detail the construction shown in the drawings and referring first to Figs. 1 to 4 inclusive, A designates the main body portion or casing of the priming cup which at its lower end is externally threaded at B so that it can be threaded into the opening in the cylinder or the like. At its upper end the priming cup has an enlarged chamber C which receives the gasoline or other fluid for starting the engine. The passage of the priming fluid from the chamber C of the priming cup into the engine cylinder or the like is controlled by a valve D governing the passage of fluid through the port of the valve seat E formed in the lower part of the casing A. The stem of this valve has a handle portion F which is provided with threads G which engage a threaded opening in the insert member J.

In both the constructions shown in Figs. 51 and 5 the insert member which has a

threaded opening engaged by the threads of the valve stem is formed as a separate piece which, after being positioned in the casing, is secured in position by suitable lugs. By forming this member as a separate piece insertable after the casing is formed, the latter can be made of sheet metal in the ordinary way of stamping. In stamping the cup the threaded end thereof is turned or upset so as to provide the valve seat E. The insert 65 member which preferably has its outer sides corresponding to the configuration of the inner wall of the central portion C' of the casing is then pushed into place and locked by any suitable means, such as by striking 70 down the lugs O from the inner walls of the casing.

In order that the valve will readily center itself upon the valve seat, I preferably form the threaded opening through which the 75 threaded valve stem extends as a separate member carried by the insert J. As shown in Fig. 1 this construction comprises a bushing H which is mounted for limited lateral movement in an elongated opening I in the 80 member J. Both above and below the plane of the insert the bushing is provided with flanges or turned-over portions K which hold it from disengagement with the insert. Upon turning the handle F to adjust the 85 valve to its seat the rotary movement given to the valve stem will, through the action of its threads on the internally threaded portion of the bushing H, cause the valve to be forced toward its seat, while the lateral play 90 permitted by the elongated slot I will allow the valve to automatically center itself upon the valve seat.

In the modified construction shown in Fig. 5 a limited movement for centering the 95 valve stem is provided by making the engagement between the threaded portion G' of the stem a loose fit with the threaded opening in the insert member J'. In this construction the bushing is omitted and this 100 loose engagement between the threaded portions utilized to permit the proper centering of the valve upon the seat. In both constructions the insert member is shown as provided with flat faces L which fit against 105 the flat inner faces of the casing A, while recesses M are provided for allowing the passage of the priming fluid downward below the insert member. Various changes in the details of construction and arrangements and 110

combinations of parts can, however, be made without departing from the scope of my invention.

What I claim as my invention is:—

- 5 1. A priming cup comprising a main body portion, the interior walls of said portion being polygonal in shape, a valve seat, a valve, a threaded stem for adjusting said valve with reference to its seat, and an insert member inserted within the polygonal walls of said main body portion and having an opening through which the threaded stem extends, the engagement between the insert and the valve stem being arranged to permit the valve to automatically center upon its seat.
- 10 2. A priming cup comprising a main body portion having a valve seat, a valve, a threaded stem for adjusting said valve toward and from its seat and an insert member secured in said casing and through which the threaded stem extends, said insert having an internally threaded bushing member through which said stem extends.
- 15 3. A priming cup comprising a main body portion having a valve seat, a valve, a threaded stem for adjusting said valve toward and from its seat and an insert member secured in said casing and through which the threaded stem extends, said insert member having a laterally movable bushing with which said threaded stem engages.
- 20 4. A priming cup comprising a main body portion having a valve seat, a valve control-
ling said seat, a longitudinally adjustable stem for actuating said valve, and a bushing having a screw-threaded engagement with said stem, said bushing being mounted to have a limited lateral movement to permit the valve to properly adjust itself to its seat.
- 25 5. A priming cup comprising a main body portion adapted to receive a supply of priming fluid, a valve for controlling the discharge of said fluid from said main body portion, a rotatable stem for said valve, and an insert member provided with an internally threaded portion through which said stem is threaded so that rotary movement of the stem will adjust the valve toward or from its seat, and lugs extending inwardly from the main body portion acting to secure said insert member to the body portion.
- 30 6. A priming cup formed of sheet metal comprising a main body portion having an integral valve seat portion formed at one end thereof, a valve, a threaded stem for

adjusting said valve toward and from its seat, and a separate insert member fixedly secured in said casing and provided with a portion having a threaded opening through which the valve stem extends.

7. In a priming cup, a main body portion composed of a cup-shaped upper end and a hollow portion of less diameter than said cup-shaped portion, the end of said hollow portion being provided with an inwardly-extending apertured flange, said body portion being formed of a stamping.

8. In a priming cup, a body portion formed of a stamping consisting of a cup-shaped upper portion and a hollow portion of lesser diameter than said cup-shaped portion, said hollow portion terminating an inwardly-extending annular flange forming a flange seat.

9. A priming cup comprising a main body portion composed of a cup-shaped upper end and a hollow portion of less diameter than said cup-shaped portion, a valve, a threaded stem for adjusting said valve toward and from its seat, an insert member, the periphery of said insert member being cut away to form a passage for the priming fluid and a projection on the body portion for retaining the insert member in its seat.

10. In a priming cup comprising a main body portion formed of sheet metal composed of a cup-shaped upper end and a hollow portion of less diameter than said cup-shaped portion, a valve, a stem for adjusting said valve toward and from its seat, an insert member resting against the inner wall of said hollow portion of less diameter and lug means for retaining said insert member.

11. In a priming cup comprising a main body portion formed of sheet metal adapted to receive a supply of liquid, a valve, a valve stem therefor, a member engaged with the body portion and adapted to carry said valve stem, and projecting means on the main body portion for retaining said member in engagement therewith.

12. In a priming cup, a body portion consisting of a cup-shaped upper portion and a hollow lower portion of lesser diameter than said cup-shaped portion, said hollow portion terminating at its extreme lower end in an inwardly-extending annular flange forming a valve seat.

In testimony whereof I affix my signature.

CHARLES W. BECK.
